DESIGN FOR A DOOR AND WINDOW GRILLE

Robert H. Hutchinson, Dallas, Tex.

Application December 10, 1937, Serial No. 73,511

Term of patent 3½ years

To all whom it may concern:

Be it known that I, Robert H. Hutchinson, a citizen of the United States, residing at Dallas, in the county of Dallas and State of Texas, have invented a new, original, and ornamental Design for Door and Window Grilles, of which the following is a specification, reference being had to the accompanying drawing, forming part thereof.

I claim:

The ornamental design for a door and window grille, as shown.

ROBERT H. HUTCHINSON.
